CLAIM

The ornamental design for the outsole for a shoe, as shown and described in the drawings.

DESCRIPTION

FIG. 1 is a bottom perspective view of an outsole for a shoe in accordance with the new design;

FIG. 2 is bottom view thereof;

FIG. 3 is a right side view thereof;

FIG. 4 is a left side view thereof;

FIG. 5 is a front view thereof;

FIG. 6 is a back view thereof;

FIG. 7 is a close up bottom perspective view of the area indicated as 7 shown in FIG. 1; and,

FIG. 8 is a cross sectional view taken along line 8—8 shown in FIG. 7.

The broken line showing a substantially rectangular shape in the arch area of FIGS. 1, 2 & 6, along with the broken parallel lines partially around the periphery in FIGS 1 & 3-8, represent the boundaries of the design with neither the lines themselves nor the areas within forming any part of the claim. The interior, unshaded portion of FIG. 5 and the broken section lines in FIG. 8 also form no part of the claim.
